UNITED STATES PATENT OFFICE.

CHARLES E. MILLER, OF CHICAGO, ILLINOIS, ASSIGNOR, BY MESNE ASSIGNMENTS, TO AMERICAN ARCH COMPANY, OF NEW YORK, N. Y., A CORPORATION OF DELAWARE.

LOCOMOTIVE-FURNACE ARCH.

1,138,053.

Specification of Letters Patent.

Patented May 4, 1915.

Application filed September 13, 1912. Serial No. 720,198.

To all whom it may concern:

Be it known that I, CHARLES E. MILLER, a citizen of the United States, and a resident of Chicago, Cook county, Illinois, have invented certain new and useful Improvements in Locomotive-Furnace Arches, of which the following is a specification.

My invention relates generally to improvements in boiler furnaces of locomotives, and relates more particularly to improvements in refractory baffle walls or arches of the type adapted for locomotive boiler furnaces equipped with arch supporting tubes.

15 The object of my invention is to improve the form, arrangement, and construction of such arches to the end that the same can be built cheaply, installed easily, and maintained in efficient working order with little attention.

Another object of my invention is to provide a sectional arch for locomotive fire boxes equipped with arch supporting tubes, which shall be easily adjustable to variations in widths of fire boxes and also to irregularities in spacing or arrangement of the arch supporting tubes, to the end that the same general arrangement of a limited number of sizes of bricks shall suit all boxes, 30 and which shall in use wedge tightly together to form a rigid arch.

Certain other objects and special advantages of my invention will appear herein-after.

35 My invention consists generally in a locomotive fire box having arch supporting tubes spaced throughout the width thereof, in combination with a baffle wall or arch comprising a plurality of side bricks resting upon the outermost arch tubes and extending upwardly and outwardly into abutment with the side sheets; said bricks having upwardly and outwardly inclined inner-end faces, and a plurality of bricks arranged upon the intermediate arch tubes and having complementary inclined faces resting upon the inclined inner edge faces of the side bricks and completing the closure between the side sheets.

40 50 My invention will be more readily understood by reference to the accompanying

drawings, forming a part of this specification and in which:

Figure 1 is a vertical section of a "wide" type locomotive fire box, equipped with a refractory front arch, embodying my invention; the section being taken on the line X—X of Fig. 2; Fig. 2 is a vertical section on the line Y—Y of Fig. 1 viewed in the direction of the arrows; Fig. 3 is a cross sectional detail of a fire box equipped with the arch of modified form, embodying my invention; Fig. 4 shows another form of locomotive arch embodying my invention; and Figs. 5 and 6 are perspective views illustrating different forms of side sheet abutting bricks.

The locomotive fire box as here shown comprises the flue sheet 2, side sheets 3—3, rear sheets 4, and the crown sheet 5. The bottom of the firebox is occupied by grate 6. The flues 7 extend forward from the upper part of the flue sheet and communicate, in manner well known, with the smoke box and stack at the front of the locomotive. The fire box is inclosed by the boiler sheet 8, which is spaced therefrom to form the front, side, and rear water legs 9, 9', and 9'' respectively. The arch tubes 10 extend from the lower part of the flue sheet 2 to the upper part of the rear sheet 4, thus occupying an inclined position. For the purpose of better installation, the tubes are usually bent, as shown, to enter the flue sheet and rear sheet at substantial right angles thereto. Water flows from the front water leg 9 through the tubes and into the rear water leg 9'', thereby protecting the tubes from burning.

The "wide" type of fire box, as here shown, is equipped with four arch tubes, but it should be understood that the number of tubes vary in the different types of fire boxes, there usually being a smaller number in the "narrow type" than in the "wide" type. In all types of fire boxes, however, the arch tubes serve the same function, the numbers thereof being varied to accommodate bricks of convenient size and shape, which is usually determined by that size of brick which can pass through the fuel door of the firebox. The arch here shown is termed a "front" arch from its

position in the fire box. Other arches are arranged on like arch tubes near the rear of the fire box, and are termed "rear" arches. I wish it to be understood that my invention is adapted both to "front" and "rear" arches, as well as to "wide" and "narrow" type fire boxes.

It will be noted that the tubes are substantially equally spaced throughout the width of the fire box. The outermost tubes 10', 10', which I shall for convenience call the "side tubes," are spaced from the side sheets, in this instance slightly more than the distance between any of two of the tubes. The spaces between the "side tubes" and side sheets are closed by a plurality of refractory bricks, 11, which are identical in form for each side of the box. They rest upon the "side tubes" in a groove 11', provided therefor on the under side of the brick. The distance between the center of groove 11' and the outer face 11'' is slightly greater than the distance between the side sheet and the tube. This causes the bricks to take a slightly upward inclined position. The brick in this position obviously wedges tightly in the place between the tube and side sheet. The face 11'' is made so that it is parallel to the side sheet when the brick occupies a slightly upward inclined position. The distance between the side sheets and "side tubes" often varies somewhat even in the same type of fire box. The bricks 11, however, readily adjust themselves to the varying distance by taking different angular positions, in every instance forming a tight joint by virtue of their wedging position. The inner face 11' of the side brick is chamfered or beveled. Thus, as will be seen in Fig. 2, the opposed side bricks 11 having their faces inclined toward the lower central part of the fire box, form an opening therebetween which is wider at the top than at the bottom; or, in other words, forming a keystone shaped opening. This space is filled by a plurality of bricks 12 and 13 respectively. The row of bricks 13 shall be referred to as the "central bricks"; the rows of bricks 12 as the "intermediate bricks"; and the bricks 12 and 13 together as the "body" of the arch. It should be understood that with some very narrow type of boxes but one central row of bricks is necessary to complete the closure between the side bricks. The "intermediate bricks" 12 are provided with inclined outer face 12' for complementary engagement with the inclined face 11' of the bricks 11. This forms one support for the brick 12, and they are of such width that the other end rests upon one of the intermediate arch tubes. The central space is closed by the "central bricks" 13, which rest upon two of the intermediate arch tubes. Both the bricks 12 and 13 have chamfered edges

12" and 13" respectively. It should be seen that any slight variation in width of the spaced relation between opposite bricks 11, due either to the distance between the side sheets or the distance between the side tubes, can be taken up by the body of the arch. For instance, if the spaced relation is greater than that shown in the drawings, the "intermediate bricks" 12 will take a lower position on the inclined face 11', and if the spaced relation is less than shown in the drawings, the bricks will rise upon the inclined face of the side bricks. The chamfered edges 12", 13" of the "intermediate" and "central" bricks enables the "intermediate" bricks and "central" bricks to take any angular position necessary to adjust the arch to the fire box dimensions.

My arch becomes more rigid with use; because the vibration of the locomotive as it travels wedges the side bricks more firmly into place between the side sheets and the side tubes and also wedges the "body" of the arch more firmly into place between the side bricks. In my arch there is no danger of the side bricks displacing the central or body bricks by a side thrust, because the thrust is taken by the side tubes upon which the side bricks rest.

Another advantage of my arch is that the brick shapes are such as can be easily made, are durable because there are no small projections or corners to be knocked off, and bricks of the same conformation may be used for all types of arches. This keeps at a minimum the number of kinds of bricks that need be made.

A further advantage of my arch is that I do not depend upon the "side bricks" to lock the whole body of the arch into place, as do many who have hitherto devised locking arches, but on the contrary depend upon the side bricks only to wedge themselves firmly into place between the side sheets and the side tubes and then the body of the arch by its weight and augmented by the vibration of the locomotive in use, wedges securely into position between the side bricks. Any portion of the side sheet can be easily gotten at for the purpose of inspection and repair by removing one of the intermediate bricks adjacent that portion and then removing the side brick.

I have shown in Fig. 5 a modified form of arch wherein the "side bricks 11" are of the same form as those described in reference to Figs. 1 and 2 and they rest upon the side tubes in like manner. The "body" of the arch is composed of a plurality of bricks 15 which are keystone-like in form and which wedge into place between the opposed inclined faces of the side bricks 11, 11. They readily accommodate themselves to fire boxes of slightly different widths as well as to slight variations in the spaced relation of

the arch supporting tubes. All of the bricks 15 forming the "body" of the arch are of the same size and conformation, one row, however, being inverted. This form of arch 5 has the advantage of requiring but two forms of brick, namely, the side brick and the center or "body" brick. The embodiment of my invention shown in Figs. 1 and 2 has the advantage of having each brick 10 supported at least on one side by the rigid arch tube, while in the form just described some of the intermediate bricks rest entirely upon the other bricks.

In Fig. 4 I have shown another embodiment of my invention wherein the "side bricks" 20 are provided with inner faces 20', 20", which are concentric to the tubes. The "body" bricks are of the same construction as those disclosed in Figs. 1 and 2. 20 This form of arch is of advantage in that the "body" bricks more readily adjust themselves to the various angular positions necessary to complete the arch in boilers of slightly different sizes, as well as fireboxes 25 wherein the spaced relation of the arch tubes varies slightly. One of the side sheets 3 is shown, greatly exaggerated, spaced nearer the center than the other. It will there be noted how the side bricks close the space by 30 taking a different angular position. The two forms of side bricks and their relation to the side arch tubes are well shown in Figs. 5 and 6 wherein the arch tubes are indicated by dotted lines.

35 In that embodiment of my invention shown in Figs. 1 and 2, I have recessed the under portion of the bricks and it is obvious that the form shown in Figs. 3 and 4 may also be constructed of recessed bricks. Such 40 bricks lighten the arch considerably and also provide a plurality of pockets on the underside which aid in the thorough commingling of the gases, and thereby effect more complete combustion.

45 My arch is adapted to be installed in the standard locomotives now in use which are equipped with such supporting tubes, and in those not equipped with arch supporting tubes by providing same with a group of 50 arch tubes.

55 My invention as herein embodied overcomes many of the defects and objections to arches now in use, as well as objections urged against those hitherto devised but not embodied in operative structures.

Having thus described my invention, I claim as new and desire to secure by Letters Patent:

1. A locomotive boiler firebox or furnace 60 in combination with a group of arch tubes arranged therein, the side tubes of which are spaced from the side sheets, side bricks having one end only resting upon the adjacent side tube and extending into engagement 65 with the side sheet, and an arch body rest-

ing upon the spaced intermediate tubing and upon the said side bricks.

2. In a locomotive boiler firebox or furnace, the combination of a group of longitudinally extending arch tubes laterally spaced in the firebox and of less width, upwardly inclined side bricks engaging the side tubes and abutting the side sheets, thereby closing the space between the side tubes and the side sheets, and an arch body substantially laterally co-extensive with said group of arch tubes and resting upon the inner faces of the side bricks and upon the intermediate arch tubes thereby closing the space between the side bricks. 70

3. In a locomotive boiler firebox, the combination with its side sheets and front and rear sheets of a plurality of arch tubes extending from the front sheet to the rear sheet and substantially equally spaced between the side sheets, side bricks having grooved under portions engaging the side tube, said brick occupying an upwardly inclined position between the side tube and the side sheet, and having an upwardly and outwardly inclined inner face, intermediate or body bricks having complementary inclined faces abutting the inclined inner faces of the side bricks, said body bricks closing the spaces between the side bricks. 80

4. In a locomotive boiler firebox, the combination with its side sheets and front and rear sheets of a plurality of arch tubes extending from the front sheet to the rear sheet and substantially equally spaced between the side sheets, a plurality of side bricks of slightly greater width than the distance between the side tubes and side sheets resting upon the side arch tubes and wedgingly abutting the side sheets, thereby closing the spaces between the side sheets and the side tubes, said side bricks having portions extending inwardly from the side tubes, said portions being beveled to form a keystone shaped space between opposite side 100 bricks, a keystone-like body portion comprising a plurality of bricks resting on the intermediate arch tubes and closing the space between the opposed side bricks by wedging abutment with the side bricks. 110

5. In a locomotive boiler firebox or furnace, the combination of a group of arch tubes laterally spaced therein, upwardly inclined side bricks abutting the side sheets and resting upon the side tubes, beveled inner faces on said side bricks within the confines of the side tubes, a body portion laterally slightly greater than the distance between the beveled faces of the opposed side bricks, said body portion having complementary beveled outer faces for engagement with the inner beveled faces of the side bricks, as and for the purpose specified. 120

6. A locomotive boiler furnace having a group of arch tubes, in combination with a 130

- refractory arch resting upon said tubes and comprising inclined side bricks resting upon the side tubes and abutting the side sheets, said side bricks forming a keystone-like closure of less width than the group of arch tubes and a keystone-like body portion of slightly greater width than the space between the side bricks, said body portion resting upon the side bricks and intermediate arch tubes and serving to close the space between the side bricks.
7. In a locomotive boiler furnace, the combination of a plurality of arch tubes spaced from the side sheets of the furnace, upwardly inclined outward extending side bricks resting upon the side arch tubes and abutting the boiler side sheets, and a keystone-like arch body comprising a plurality of bricks resting upon the intermediate arch tube and the side bricks and closing the space therebetween.
8. In a locomotive boiler firebox, the combination of a group of arch tubes of less width than the firebox, arch side portions comprising a plurality of upwardly inclined outwardly extending bricks resting upon the side tubes wedged into position between the tube and side sheet, wedge-like inner edges on said side bricks within the confine of the side tubes, and a body arch portion slightly less extensive than the arch tubes and more extensive than the space between opposite side bricks, comprising a plurality of bricks, one edge of which is supported on the intermediate arch tubes and the outer edge of which rests upon the wedge-like inner edges of the side brick, as and for the purpose specified.
9. An arch for locomotive boiler furnaces supported by arch tubes and comprising bricks supported by arch tubes at their inner ends and leaning against the side sheet of the firebox at their outer ends, in combination with intermediate bricks resting upon intermediate arch tubes, the outer ends of the intermediate bricks resting upon and wedgingly engaging the inner ends of the side bricks.
10. The herein described improvement in locomotive fire box arches, comprising a side brick for such arches, said brick having its ends beveled in substantially parallel relation to respectively engage a side sheet and be engaged by another arch brick, and said side brick having an arch tube groove or socket in its under side parallel with and adjacent the end which is adapted to engage another brick, for the purposes described.
- In testimony whereof, I have hereunto set my hand, this 9th day of September, 1912, in the presence of two subscribing witnesses.
- CHARLES E. MILLER.
